(57) **CLAIM**

The ornamental design for an automatic animal feeder, as shown and described.

DESCRIPTION

FIG. 1 is a front perspective view of an automatic animal feeder showing my new design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom view thereof.

The broken lines depict unclaimed features of the automatic animal feeder, shown for purposes of illustration, that form no part of the claimed design.
